(57) **CLAIM**

The ornamental design for a bucket, as shown and described.

DESCRIPTION

FIG. 1 is a perspective view of a bucket showing my new design;

FIG. 2 is another perspective view of the bucket;

FIG. 3 is a rear view of the bucket;

FIG. 4 is a front view of the bucket;

FIG. 5 is a right side view of the bucket;

FIG. 6 is a left side view of the bucket;

FIG. 7 is a bottom view of the bucket; and,

FIG. 8 is a top view of the bucket.

The broken lines shown in the drawings of a handle and wheels are for illustrative purposes only and form no part of the claimed design.
